(57) **CLAIM**

The ornamental design for a mobile power supply, as shown and described.

DESCRIPTION

1. Mobile power supply

Figure 1.1 is a front elevational view of the mobile power supply;

Figure 1.2 is a rear elevational view of the mobile power supply of Figure 1.1;

Figure 1.3 is a left-side elevational view of the mobile power supply of Figure 1.1;

Figure 1.4 is a right-side elevational view of the mobile power supply of Figure 1.1;

Figure 1.5 is a top plan view of the mobile power supply of Figure 1.1;

Figure 1.6 is a bottom plan view of the mobile power supply of Figure 1.1;

Figure 1.7 is a left-side and front perspective view of the mobile power supply of Figure 1.1;

Figure 1.8 is a left-side elevational view of the mobile power supply of Figure 1.1 in a use configuration with environment;

Figure 1.9 is a side elevational view of the mobile power supply of Figure 1.1 in a use configuration with environment; and

Figure 1.10 is a front elevational view of the mobile power supply of Figure 1.1 in a use configuration with environment.

Possible use: store and provide electric energy, support DC and AC power supply, and is suitable for indoor, courtyard, outdoor, RV, camping, rescue and other emergency environment. The broken lines in Figures 1.8, 1.9, and 1.10 depict environment that forms not part of the claimed design. The dashed broken lines in Figures 1.1, 1.6, and 1.7 depict portions of the mobile power supply that form no part of the claimed design.

1 Claim, 10 Drawing Sheets
